CAN PIERCING AND DISPENSING DEVICE

Frederick A. Prahl, New York, N. Y., assignor to
 Continental Can Company, Inc., New York,
 N. Y., a corporation of New York

Application July 13, 1933. Serial No. 680,324

6 Claims. (Cl. 221—23)

The invention relates to new and useful improvements in a can piercing and dispensing device which is particularly adapted for attachment to a hermetically sealed metal can to be used for dispensing the contents thereof.

An object of the invention is to provide a can dispensing device wherein the dispensing device contacts with the double seam of the can, forming a liquid-tight joint therewith, and is rigidly secured to the can by cooperating parts associated with the dispensing device and can, which dispensing device is also provided with a cutter for piercing the end wall of the can for forming a dispensing opening therethrough.

A further object of the invention is to provide a dispensing device of the above type wherein said opening may be first cut and the dispensing device caused to contact with the double seam and the dispensing device subsequently joined to the can.

These and other objects will in part be obvious and will in part be hereinafter more fully described.

In the drawing:

Figure 1 is a view partly in side elevation and partly in vertical section through a can and dispensing device embodying the improvements with the dispensing device attached to the can.

Figure 2 is a view partly in side elevation and partly in vertical section showing the can with the oil dispensing device attached thereto inverted for the dispensing of the contents of the can into the crank case chamber of an engine.

Figure 3 is a bottom plan view of the dispensing device detached from a can.

Figure 4 is an enlarged vertical section through a portion of the container and the can, with the container attached to the can.

Figure 5 is a sectional view of a portion of the clamping means which cooperates with the can in the securing of the dispensing device to the can.

Figure 6 is an end view of a can embodying the improvements after it has been cut, the contents dispensed, and the dispensing device removed.

The invention is directed to a combined can and oil dispensing device for use in connection with the dispensing of lubricating oil marketed in hermetically sealed metal cans. The oil is put up by the original dispenser in sealed cans and is sold in these original packages at the filling stations. The cans may be opened in the presence of the customer and emptied into the chamber where it is to be utilized for lubricating purposes through the aid of the improved dispensing device. The dispensing device includes a

funnel having a body portion to which is attached a cutter used for piercing the can end. The can, after the end is seamed thereto, is shaped or deformed so as to provide spaces in the double seam where the diameter of the can is reduced slightly. These spaces are of similar shape and disposed in the double seam so that the distances between the recesses are all equal. The body portion of the dispensing device is provided with a recess adapted to receive a resilient gasket which is so disposed as to contact with the outer face of the deformed double seam and provide a liquid-tight joint therebetween. Attached to the body portion is a clamping ring. Said clamping ring is mounted on the body portion so that it may be rotated thereon. The clamping ring has an opening therethrough and at spaced intervals there are lugs projecting inwardly or radially of the opening. These lugs are shaped to conform to the recesses in the double seam of the can so that the clamping ring can be lowered over the double seam, placing the lugs just beneath the same. A turning of the ring will cause the dispensing device to be clamped to the can. These lugs on the ring are inclined so that the turning of the ring draws the gasket into tight sealing contact with the deformed double seam.

Referring more in detail to the drawing, the can to which the dispensing device is attached is illustrated at 1 in the drawing. Said can has an end 2 secured thereto by a seam which is hermetic or airtight, and this seam is preferably formed by the folding of the metal parts and is referred to as a double seam. The double seam joining the end 2 to the body portion 1 is indicated at 3 in the drawing. After this double seam has been formed, it is then reshaped or deformed so as to provide recesses 4, 5 and 6. These recesses are all similarly shaped and are disposed an equal distance from each other. As shown in the drawing, there are three of these recesses and the centers of the recesses are 120 degrees apart. These recesses are formed by pressing the double seam inwardly so as to leave the diameter of the can at the recess substantially the same as the diameter of the body of the can, while the diameter of the double seam between the recesses is as usual, i. e. larger than the diameter of the can. This is caused by the double seam being formed between the outwardly projecting flange on the can body and the overhanging flange of the can end.

The oil dispensing device consists of a funnel having a spout portion 7 which is formed integral with the body portion 8 as it tapers into the spout. The body portion 8 is provided at the open end 110

thereof with the laterally projecting ledge 9. There is a recess in said body portion which is indicated at 10 and located in this recess is a resilient gasket 11. This gasket is adapted to contact 5 with the deformed or reshaped double seam 3 as indicated in Figs. 1 and 4 of the drawing.

Attached to the body portion of the dispensing device are three cutters 12, 13 and 14. These cutters are all similar in construction, and the 10 description of one will answer for the others. Each cutter includes a piercing point 15 formed at the outer end of the cutting blade 16. This cutting blade is shaped so as to cut the can end close to the double seam and along the double 15 seam as indicated at *a* in Fig. 6 of the drawing. Extending laterally from the blade portion 16 are wings 17 and 18. These wings are each provided with an opening 19 and with cutting edges indicated at 20. It is understood that there is a 20 cutting edge leading to the piercing point 15 along the lower edge of the blade 16 as viewed in Fig. 4. These cutting edges merge into the cutting edges 20 formed on the wings 17 and 18. The cutting edges 20 cut the can end along the lines *b*—*b* in 25 Fig. 6 of the drawing. The metal cut out by the cutter contacts with the wings and is rolled downwardly and inwardly as indicated at *c* in Fig. 4 of the drawing. This produces in the can end 3 relatively large dispensing openings which are 30 disposed so that their centers are 120 degrees apart. The cutters are attached to the body portion of the dispensing device and project beyond the open end a sufficient distance so that all the openings will be formed before the gasket 11 is 35 brought into contact with the double seam. The cutting of the end is accomplished by placing the can on a solid foundation, then placing the piercing point just inside of the double seam of the end and by downward pressure on the dispensing device the cutters are caused to pierce 40 the end and the metal and form the opening.

Surrounding the projecting ledge 9 is a ring 22. Attached to the ring 22 is a plate 23 which overlies the upper face of the ledge as viewed in Figs. 45 1 and 4. Said plate is connected to the ring by suitable bolts 24. The ring has an opening 25 therethrough. The edge of the opening 25 is provided with lugs projecting inwardly or radially of the opening. These lugs are indicated 50 at 26. The lugs are disposed with their centers 120 degrees apart and they are so proportioned that when the ring, which is only slightly larger in diameter than the originally formed double seam, is placed over the double seam, bringing 55 the gasket into contact therewith, these lugs pass down through the recesses 4, 5 and 6, respectively. This places the lugs so that the advanced edge 26a thereof is below the double seam. By turning the ring in the direction of the arrow of Fig. 60 5, the lug is placed beneath the double seam at the sides of the recesses and will contact therewith and draw the dispensing device downward until the gasket is brought into tight sealing engagement with the double seam. This forcing of 65 the dispensing device downward is accomplished by the inclination of the lugs 26. These lugs cooperating with the double seam between the recesses serve as a means for rigidly attaching the dispensing device to the can. The turning of 70 the ring is to bring about this attachment of the dispensing device to the can. The body portion of the dispensing device of course does not turn as the cutters are in the holes formed in the end. The longitudinal movement of the dispensing device into tight sealing contact with the double 75

seam is not in any way restrained by the cutters, for the reason that the openings are fully formed at this time and there is little or no cutting of the metal which takes place during the period of clamping the dispensing device to the can.

80

The cutters of the oil dispensing device are placed in contact with the end of the can and the openings are formed therein while the can rests on a solid support. The ring is then turned to firmly join the dispensing device to the can, after which the can with the dispensing device attached is inverted to a position such as shown for example in Fig. 2 and the spout inserted in the opening 27 of the crank casing 28 for thus dispensing the lubricating oil into the chamber 90 where it is to be used for lubricating purposes.

90

It is obvious that minor changes in the details of construction may be made without departing from the spirit of the invention as set forth in the appended claims.

95

Having thus described the invention, what I claim as new and desire to secure by Letters Patent, is:

1. The combination of a can and an oil dispensing device including a body portion, a spout formed integral with said body portion, a resilient gasket attached to said body portion and adapted to contact with the double seam of the can, a plurality of cutters attached within the body portion of the dispensing device and having their piercing points and cutting edges projecting from the open end of the body portion, said body portion of the dispensing device and said can having cooperating devices whereby the gasket may be drawn into tight sealing contact with the double seam of the can and the dispensing device rigidly attached to the can.

100

2. The combination of a can and an oil dispensing device including a body portion, a spout formed integral with said body portion, a resilient gasket attached to said body portion and adapted to contact with the double seam of the can, a plurality of cutters attached within the body portion of the dispensing device and having their piercing points and cutting edges projecting 105 from the open end of the body portion, said body portion of the dispensing device and said can having cooperating devices whereby the gasket may be drawn into tight sealing contact with the double seam of the can and the dispensing device rigidly attached to the can.

110

2. The combination of a can and an oil dispensing device including a body portion, a spout formed integral with said body portion, a resilient gasket attached to said body portion and adapted to contact with the double seam of the can, a plurality of cutters attached within the body portion of the dispensing device and having their piercing points and cutting edges projecting 115 from the open end of the body portion, said body portion of the dispensing device and said can having cooperating devices whereby the gasket may be drawn into tight sealing contact with the double seam of the can and the dispensing device rigidly attached to the can, each of said cutters including cutting edges inclined away 120 from the piercing point for cutting said can end along the double seam and thence along lines leading inwardly from the double seam.

125

3. The combination of a can and an oil dispensing device including a body portion, a spout formed integral with said body portion, a resilient gasket attached to said body portion and adapted to contact with the double seam of the can, a plurality of cutters attached within the body portion of the dispensing device and having their piercing points and cutting edges projecting from the open end of the body portion, said body portion of the dispensing device and said can having cooperating devices whereby the gasket may be drawn into tight sealing contact with the double seam of the can and the dispensing device rigidly attached to the can, each 130 of said cutters including a blade having a piercing point with cutting edges leading therefrom and side wings extending inwardly from the blade substantially parallel to each other and having cutting edges arranged so that the metal is progressively cut from the piercing point along the 140

130

145

150

double seam and then along parallel lines extending inwardly from the double seam.

4. The combination of a can and an oil dispensing device including a body portion, a spout formed integral with said body portion, a resilient gasket attached to said body portion and adapted to contact with the double seam of the can, a plurality of cutters attached within the body portion of the dispensing device and having their piercing points and cutting edges projecting from the open end of the body portion, said body portion of the dispensing device and said can having cooperating devices whereby the gasket may be drawn into tight sealing contact 15 with the double seam of the can and the dispensing device rigidly attached to the can, each of said cutters including a blade having a piercing point with cutting edges leading therefrom and side wings extending inwardly from the blade 20 substantially parallel to each other and having cutting edges arranged so that the metal is progressively cut from the piercing point along the double seam and then along parallel lines extending inwardly from the double seam, said 25 wings having openings therethrough disposed so as to drain the can during the dispensing of the contents thereof.

5. The combination of a can and an oil dispensing device including a body portion, a spout formed integral with said body portion, a resilient gasket attached to said body portion and adapted to contact with the double seam of the can, a plurality of cutters attached within the body portion of the dispensing device and hav-

ing their piercing points and cutting edges projecting from the open end of the body portion, said can having the double seam thereof deformed so as to provide spaced recesses of less radial distance from the center of the can than the outer face of the double seam, and said body portion of the oil dispensing device having means adapted to pass through said recesses and to be turned beneath the double seam for drawing the resilient gasket into tight sealing contact with the double seam.

6. The combination of a can and an oil dispensing device including a body portion, a spout formed integral with said body portion, a resilient gasket attached to said body portion and adapted to contact with the double seam of the can, a plurality of cutters attached within the body portion of the dispensing device and having their piercing points and cutting edges projecting from the open end of the body portion, said can having the double seam thereof deformed so as to provide spaced recesses of less radial distance from the center of the can than the outer face of the double seam, a ring rotatably attached to said body portion and having an opening of slightly larger diameter than that of the double seam of the can, said ring having inwardly projecting inclined lugs shaped and disposed so as to pass through said recesses and beneath the double seam when the ring is rotated for drawing the resilient gasket into sealing contact with the double seam of the can.
